UNITED STATES PATENT OFFICE

FREDERIC MEIER, OF CHICAGO, ILLINOIS

CONTAINER

Application filed May 11, 1931. Serial No. 536,468.

This invention relates to containers, and particularly to containers in which are enclosed heavy liquids, such as oils, paints and the like. By containers I refer to any ordinary liquid container, such as metallic cans, pails, or the like, and for convenience will refer to them herein merely as cans. It is common to enclose linseed oils, paints and the like in cans which have removable friction tops, and particularly tops which are known by the trade as double- or triple-tight. These tops may be conveniently removed by the user of the goods and can be replaced readily, and at all times will be sufficiently tight to prevent any leakage of the goods. But when oils or paints are packed in this manner, it occasionally happens that, because of increase in temperature, there will be a tendency for some air to be forced out of the cans and then air is forced inwardly as the temperature decreases. This is what is known in the trade as "breathing" of the containers. In this manner, the enclosed substance may be more or less injured. The air that enters, although in very small quantities, causes some oxidation that is objectionable.

One of the objects of my invention is to hermetically seal the cans so that this breathing process is entirely eliminated but, at the same time, I provide means which may be very conveniently opened by the user of the goods. In connection with this, I have found it desirable, for reasons hereinafter given, to provide means for testing the cans after the hermetical sealing, and for filling the cans, for protecting the sealing means from injury, and also for resealing the cans after they have been opened, so that the leakage is substantially eliminated. The initial hermetical sealing of the can permits the storing thereof for unlimited time without injury to the contents, and as it is unsealed only when the contents are to be used in a relatively short time, the resealing, although not altogether hermetical, is sufficient for the temporary purpose.

The accompanying drawing is a central sectional elevation of a can which has sealing and protecting means attached thereto which embodies the features of my invention.

The invention is applicable to any type of can but more particularly to large cans which are to contain heavy oils, paints and the like. The can illustrated comprises the ordinary body 2 which has what is called a double-tight annular rim 3 on its upper end, with an opening 4 in the central portion thereof. In this opening, I insert a closure 5 which may be of any suitable material, either fibrous or metallic. I prefer for the purpose to use a metal closure which is relatively thin, so that it may be very readily punctured and cut by an ordinary knife. The edge of this closure is hermetically sealed to the rim in any suitable manner, such as by hemming, bumping, soldering, welding or gluing. I prefer to connect the edges of the container with the rim by hemming as indicated, and then sweating solder in the joint, so as to insure hermetical sealing.

With the can so sealed, if the closure is sufficiently thin, the user of the goods may very readily cut or tear the closure out in any ordinary manner. But to provide a closure which can be thus operated on readily, it must be protected when empty against injury by handling or otherwise, and also it must be strengthened in order to prevent the heavy material from bursting open the closure when the can is full and may be roughly handled. For this protection, I provide a top for the can which is suitably formed, so that it may be conveniently forced on the rim of the can and held thereon by friction. For this purpose, I prefer the top 6 which has an annular loop 7 which coacts with the loop 8 of the rim, so as to produce a friction-tight connection between the two elements. When this top is forced in place, it protects the closure 5 from any injury from the outside or inside. Preferably, the central portion of the top is bent downward, so as to lie on or close to the closure.

When the can is to be opened for use, the top is removed in an ordinary manner by prying upwardly the edges thereof, and the closure 5 is cut or torn out in any suitable manner, and so much of the material contained in the can as may be desired is used. The can may then be substantially hermeti-

cally sealed by forcing on the top in an ordinary manner.

In order to hermetically seal the container in this manner, however, I have found it 5 desirable to test the sealing of the closure to determine whether there is any leakage whatever of air under pressure. For this purpose, I prefer to provide an opening 9 in the bottom of the can and, by suitable means, so 10 much interior air pressure as may be desired is provided, in order to test for leakage. This opening also is used for filling the can with the material. The opening is then sealed up in an ordinary manner.

15 The opening in the bottom is desirable for testing and filling, for the reason that to form an opening in the closure 5 would so weaken the thin material of which the closure is made as to make it difficult to properly test and seal 20 the opening. But, with the opening in the bottom, which is of relatively much heavier material, there is no danger of injury, and the opening may be readily closed by soldering thereon an ordinary cap 10, and the testing 25 is materially simplified by having the opening in the bottom instead of in the top which is to be tested.

30 The opening in the bottom, however, may be formed by leaving off the entire bottom, as is customary with cans in the packing industry, and as called by the trade "open top" cans. After the cans are filled, the one-piece bottom is then hermetically sealed onto the can body. This process may be used with smaller packages. With larger packages, preferably an 35 opening 9 is used.

35 This method of sealing cans full of liquids permits their being transported by mail, and provides against rough handling. The 40 double- or triple-tight connection of the top is necessary in order to prevent the top being forced off by material pressure outwardly on one side of the top, and also to reduce breathing to a minimum after the 45 closure is removed.

50 It sometimes happens that, because of jarring, variations in temperature, or the like, the thin metal of the closure 5 becomes fatigued and tends to crack adjacent the connection 55 with the top, or the connection itself may break sufficiently to cause trouble. To overcome this, I provide an annular loop 11 just inside of the connection. This loop yields slightly under vibrations or changes due to 60 temperature changes, thus relieving the metal outside the loop of its strain and cracking tendency.

65 It will be understood that the sealing method which I have provided allows the goods to be packed under a partial vacuum, for example by means of the ordinary mechanical vacuum process, as leakage of the air into the cans when sealed is entirely avoided.

I claim as my invention:

A container comprising a body having an upper and a lower end, the upper end having a rim with a large opening in its central portion, a closure with its edge hermetically sealed to the edge of the opening, and an imperforate top over said closure, the periphery of the top having a friction connection with said rim, said closure having an annular yieldable loop therein immediately inside of its sealed edge.

70 In testimony whereof, I hereunto set my hand.

FREDERIC MEIER.
